DESIGN FOR A SCARF OR SIMILAR ARTICLE

Harry Rosenbaum, Denver, Colo.

Application March 25, 1946, Serial No. 127,912

Term of patent 7 years

(Cl. D3—12)

To all whom it may concern:

Be it known that I, Harry Rosenbaum, a citizen of the United States of America, residing at Denver, in the county of Denver and State of Colorado, have invented a new, original, and ornamental Design for Scarfs or Similar Articles, of which the following is a specification, reference being had to the accompanying drawing, forming part thereof.

The drawing illustrates a face view of a scarf or similar article, showing my new design.

I claim:

The ornamental design for a scarf or similar article, as shown.

HARRY ROSENBAUM.
